UNITED STATES PATENT OFFICE.

ELMER U. AMES, OF PHILADELPHIA, PENNSYLVANIA, ASSIGNOR TO H. BRINTON COMPANY, OF PHILADELPHIA, PENNSYLVANIA, A CORPORATION OF PENNSYLVANIA.

KNITTING-MACHINE.

1,340,695.

Specification of Letters Patent. Patented May 18, 1920.

Application filed November 8, 1915. Serial No. 60,300.

To all whom it may concern:

Be it known that I, ELMER U. AMES, a citizen of the United States, residing in Philadelphia, Pennsylvania, have invented 5 a certain Knitting-Machine, (being a continuation in part of my application for U. S. Patent, Serial No. 7111, filed February 9, 1915), of which the following is a specification.

10 One object of this invention is to provide relatively simple, substantial and accessible mechanism for controlling the operation of the yarn guiding fingers of a circular knitting machine, the invention contemplating 15 such an arrangement of parts as will permit the raising of the latch ring to an inoperative position and its lowering to an operative position without changing the operative connection between the yarn guiding 20 fingers carried by said ring and the cams whereby their action is controlled.

A further object of the invention is to provide novel means for maintaining constant or invariable the angle at which yarn 25 is fed to the needles regardless of the movement of the cam ring to vary the length of the stitches, the various parts being arranged so that the cam and latch rings are 30 mechanically connected and caused to move with the yarn guides in such manner as to accomplish this end.

It is also desired that the mechanism operatively connecting the yarn-serving fingers or guides with their controlling cams shall be so arranged as to permit of the 35 latch ring adjustment without interfering with the proper operation of the machine.

These objects and other advantageous ends I secure as hereinafter set forth, reference being had to the accompanying drawings, in which,

Figures 1 and 2 are respectively a side elevation and plan of a circular knitting machine embodying my invention;

45 Fig. 3 is a vertical section on the line *a—a*, Fig. 2;

Fig. 4 is an elevation partly in section illustrating certain of the parts of the machine in positions different from those illustrated in Fig. 1;

Fig. 5 is a fragmentary elevation showing one of the features of my invention; and

50 Fig. 6 is an elevation partly in section illustrating the reinforcing yarn guide with certain of its associated parts, in the several

positions occupied under conditions of use of the machine to which my invention is applied.

In the above drawings, 1 is a frame supporting a needle cylinder 2 which, during 60 the operation of the machine, alternately receives a rotary and an oscillatory movement and is of any suitable construction, having grooves 3 for the reception of needles 4. The lower end of said cylinder fits with- 65 in a ring 5 having set screws 6 placed to enter recesses 7 in the lower end of said cylinder so that this latter may be removed by backing off said screws. Fixed to the lower portion of the ring 9 is a gear 8 70 through which power is applied for driving the cylinder.

The frame 1 is provided with a vertically extending guideway 28 in which is slidably mounted a post 27 formed as part of the 75 cam ring 63 and having a flange 29 formed to constitute a pocket for one end of a coiled spring 30 whose opposite end engages said frame so as to be capable of moving the post upward after it has been depressed. The lower end of the post 27 is connected through a link 31 and a rod 31^a to an arm 32 of a bell crank lever 33, which is fulcrumed on a shaft 34 mounted in suitable bearings in the frame 1. The second 85 arm 35 of this lever is placed to be actuated by a series of cams, of which one is shown at 36, on a main cam drum 37, in order to periodically lower the post 27 and with it the cam ring 63 during the knitting of cer- 90 tain portions of a stocking.

A latch ring 38 is pivotally mounted on a pin 39 carried by a forked structure 27^a mounted so as to be vertically adjustable as well as adjustable in a horizontal plane on 95 the post 27, there being a set screw 27^b whereby it may be retained in any given position. Said latch ring normally occupies a position directly over the needle cylinder so that the needles when moved upwardly 10 will pass within it and is adjusted by means of a screw 40 which extends through a lug 41 thereon and has its inner end in contact with said forked structure 27^a, so that said latch ring cannot move down below a 10 horizontal plane.

The latch ring has a radial extension 43 in which is formed an opening 38^a serving as a guideway for yarn-guide actuating jacks 42 which are slidable toward and from 11

the needles. In order to hold these jacks in place while permitting their limited longitudinal movement I provide two pins 46 and 47 which extend through the walls of said extension across the opening 38 and pass through slots 44 and 45 in said jacks. Yarn guide fingers 48^a, 48^b, 48^c and 48^d are pivotally mounted on a shaft 49 supported in the extension of the latch ring and each has an actuating arm 50 fitting within a notch 51 in a coating one of the jacks 42, so that a sliding movement of one of the latter will raise or lower its particular yarn guide within the latch ring 38 in order to withdraw yarn from or serve it to the needles.

For the purpose of actuating the jacks I provide a number of bell crank levers 52^a, 52^b, 52^c and 52^d, movably mounted on a shaft 20 53 carried in an extension 54 of the frame 1. Each of these levers has an arm provided with an adjusting screw 56 whose lower end is placed to engage a flat buffer spring 57 also projecting from said arm, and the main 25 drum 37 has cams 58 placed to engage these springs at definite times during the operation of the machine, so as to move the levers into the position occupied by the lever 52^c in Fig. 3. In addition to the above I also 30 provide a yarn guide 48 pivotally mounted on a bracket carried by the latch ring extension in position to feed a reinforcing yarn to the needles, the others of the yarn guides being actuated by cams on the pattern 35 drum to insert the yarns required in knitting a stocking. For example, the guide 48^c may be used to supply the yarn for the body of the foot of the stocking, while the fingers 48^a, 48^b and 48^d may be employed to 40 feed threads of different kinds, sizes or colors as desired.

Each jack 42 at the lower part of its rear end has a projection 42^a placed below the pivotal support 39 of the latch ring and is 45 forced toward its actuating lever by a spring 59; one end of each spring being attached to a pin 60 on the extension 43 while its other end is attached to a pin 61 on the jack.

When the latch ring 38 is in its horizontal position and the lever 52^a has been moved to engage and slide the jack 42 into its extreme forward position, the yarn guide 48^a is thrown up out of action. If on the other hand the cam 58 on the pattern drum 37 is 55 moved from under the lever 52^a, the spring 59 will move said jack 42 rearwardly and permit the yarn guide to move down into a position in which it can feed yarn to the needles.

60 The above jack-actuating levers 52^a etc., are so shaped and mounted that when they are moved by the cams 58 to their highest positions, their jack engaging surfaces are substantially vertical, thus permitting vertical movement of the post 27 without af-

fecting the position of the yarn guides. On the other hand, when the cams 58 move from under the levers 52^a, etc., and allow them to drop to their lowest positions, their jack engaging surfaces will occupy positions 70 clear of the jacks 42 as shown in the case of the lever 52^c, Fig. 4. By the above described arrangement of jacks and jack operating levers the latch ring 38 may be freely moved into and out of its operative 75 position without interference from any of the associated mechanism, since when it is lowered, those jacks 42 which had moved their yarn guides up before the latch ring was raised, will engage the vertical surfaces of their respective actuating levers and will be again moved on the extension 43, thereby again moving said fingers into 80 inoperative positions.

In Fig. 4 I have shown the latch ring in 85 its partly raised position, with the projecting end of one of the jacks 42 in engagement with the actuating face of the lever 52^c, so that a downward movement of said ring will cause said jack to be moved inwardly, thereby raising the yarn-guide finger 48^c out of action. If the latch ring be moved upwardly from the position shown in Fig. 4, the spring 59 will move the jack 42 outwardly, thus drawing the yarn finger 95 within the opening of the extension of the latch ring.

The reinforcing yarn guide 48 tends to move into the lower position indicated in dotted lines in Fig. 6 under the action of a 100 spring 134 mounted within a cylindrical casing 135, in which position it will feed yarn to the needles. Said guide 48 may be moved into an inoperative or raised position by means of a jack 42^b slidably mounted like the jacks 42 and actuated by a lever 52, which may be shifted as described in connection with the levers 52^a to 52^d inclusive. Said jack 42^b may be moved by a spring 59^a away from the yarn guide 48 to 110 permit the spring 134 to lower it into operative position. For controlling this movement of the parts I provide a cam 52^f on the pattern drum 37 which acts on an arm of the lever 52 to move the jack 42^b into engagement with the yarn guide 48 and swing it up and wholly out of action as required in order to allow the long butt needles to pass it when they are in their highest positions, as during the knitting of the heel 115 and toe.

The lever 52 is connected by a link 136 to one arm of a lever 138 pivoted to a depending lug 139 on the frame 1. The other arm of said lever is provided with an antifriction roller 141 which, when the lever 52 is disengaged from the cam 52^f on the drum 37, may be engaged by a cam 142 on the bottom of the needle cylinder, in order to raise the yarn guide 48 out of action during the 125 130

- knitting of the unreinforced part of the stocking. If it is desired that the mechanism shall knit a stocking with its sole portion reinforced, the length of this cam 142, is such as to be inversely proportional to the number of needles to which it is desired to feed the reinforcing yarn; it being obvious that at a definite point in the rotation of the needle cylinder, said cam will actuate the lever 138 in such manner as to move the reinforcing yarn guide 48 upwardly away from the needles, and prevent it from feeding reinforcing yarn to those needles which, for example, knit the upper or instep portion of the foot.
- On the other hand, as the cam 142 passes out of engagement with the roller 141, the lever 138 will be moved by the jack 42^b under the action of the spring 59^a transmitted through the lever 52 and link 136, and the yarn guide will be moved into its lower or operative position in which it feeds the reinforcing yarn to the needles for knitting the sole part of the foot. The cam 142 and the spring 134 will thus act during each revolution of the needle cylinder to move the yarn guide 48 out of and into operative position relatively to the needles, it being understood that if said cam has an angular length of 180 degrees, the reinforcing yarn guide 48 will remain in operative position to feed reinforcing yarn to one-half the needles in the cylinder and will then be moved into an inoperative position in which it withdraws the reinforcing yarn from the remainder of the needles. Obviously if the length of this cam be increased, it results in a decrease in the number of needles to which reinforcing yarn is fed and vice versa.
- If therefore during the knitting of the foot portion of a stocking, the reinforcing yarn guide is alternately moved into and out of operative position at such times that reinforcing yarn is fed to but one-half of the needles in the needle cylinder, one-half of the knitted web will be reinforced as is desired in the sole portion of the foot.
- The movement of the pattern drum 37 is such that when the foot portion of the stocking is to be knitted, the cam 52^c will pass out of engagement with the lever 52, which will be moved by the spring 59^a in the direction of the arrow X, Fig. 1, thereby allowing the jack 42^b to move outwardly. The action frees the yarn guide 48 so that its movement into and out of operative position may be affected by the cam 142. By the rotation of the needle cylinder during the knitting of the foot portion of a stocking, the roller 141 is moved down by the cam 142, causing the yarn guide 48 to be moved out of operative position for a certain time during each revolution, though not for such a distance as that caused by the cam 52^c on the drum 37. In any case however the outward movements of said yarn guide 48 are sufficient to prevent it from feeding yarn to the needles.
- In order to knit the reinforced sole of the stocking, the cam 52^c is so placed upon the pattern drum 37 that when the machine starts to knit said portion, it will move from under the arm of the lever 52, thus moving the yarn guide 48 into a position to serve the reinforcing yarn; it being noted that for each revolution of the needle cylinder 2 the cam 142 will move the lever 138 and thereby cause a movement of said guide into and out of its yarn feeding position.
- While I have described a certain definite construction of yarn guide for feeding the reinforcing yarn, it will be understood that other forms, such as the main yarn guides illustrated, may be employed to serve such reinforcing yarn, and the main yarn may be served from any one of the guides 48^a, etc.
- It is particularly to be noted that as shown in Fig. 5, by rigidly connecting the cam ring and the yarn changer comprised by the latch ring 38 and its associated parts, the angle of delivery of the yarn relatively to the needle wave remains constant irrespective of the changes in the position of said cam ring incident to the knitting of a stocking. That is to say, there can be no variation of the angle at which yarn is fed when the cam ring moves up or down to lengthen or shorten the stitches, since owing to the rigid connection between said ring and yarn changer, the latch ring with the yarn directing members will move up or down at the same time and to the same extent. This angle may be adjusted however by moving the forked structure 27^a up or down on the post 27.
- Under operating conditions the yarn passes from the yarn guides to the corner of the throat plate 65 and from thence to the point at which it is engaged by the needles. Ordinarily when the cam ring is lowered to cause lengthening of the stitches, the needles move down bodily so that the line of the yarn between said throat plate and the point at which said yarn is engaged by the needles approaches the adjacent line of travel of the needles, increasing the likelihood of the yarn passing above rather than into the hooks of the needles. On the other hand when the cam ring is raised, the movement of the above mentioned line of the yarn away from the line of travel of the needles frequently causes the yarn to be pinched between the latch and the wall of each needle as said latch closes. By connecting the yarn changing device with the cam ring as previously described, the angle of yarn delivery remains constant regardless of the position of said ring.

I claim:—

1. The combination in a knitting machine

of a needle support; needles therein; a latch ring; a jack; a finger for feeding yarn to the needles, actuated by said jack; and a lever normally disconnected from the jack having an actuating surface perpendicular to the line of movement of the jack for actuating the same, the jack, the finger and the lever all being movable in the same plane.

2. The combination in a knitting machine of a needle support; needles therein; a latch ring; a pivotal support for said latch ring; a finger for feeding yarn to the needles; a jack slideable on the latch ring for moving said yarn finger and having a portion below the axis of said pivotal support; means for moving said jack in one direction to move said finger into one position; and a structure movable into contact with that part of said jack below the pivotal support for moving the jack in another direction to move said finger into a second position.

3. The combination in a knitting machine of a needle support; needles therein; a latch ring; a pivotal support for said latch ring; a finger for feeding yarn to the needles; a jack slideable on the latch ring to move said yarn finger and having a portion below the pivot of said latch ring; means for sliding said jack in one direction to move said finger into one position; a lever having a surface movable into engagement with said lower portion of the jack to slide it in another direction to move said finger into a second position, said lever surface being substantially vertical when in engagement with the jack.

4. The combination in a knitting machine of a cylinder; a latch ring; a pivotal support for said latch ring; a yarn feeding finger; a jack for moving said yarn finger; means for sliding said jack in one direction to move said finger into one position; a lever having a surface movable into engagement with said jack to slide the latter in another direction to move said finger into a second position, said lever surface being substantially vertical when in engagement with the jack; and means for automatically moving said pivotal support to vary the distance between the latch ring and the cylinder.

5. The combination in a knitting machine of a needle support; needles therein; a latch ring; a pivotal support for said latch ring; a finger for feeding yarn to the needles; a jack slideable on said latch ring for moving said yarn finger; means for sliding said jack in one direction to move said finger into one position; a lever movable into contact with the jack to slide it in another direction to move said finger into a second position; and means for holding said lever in engagement with the jack to hold said finger in an inoperative position, the finger, the jack and the lever all being movable in the same plane.

6. The combination in a knitting machine of a needle support; needles therein; a latch

ring; a jack supported by said latch ring; a finger actuated by said jack for feeding yarn to the needles; means for moving said jack in one direction to move said finger into one position; a lever for moving the jack in another direction for moving said finger into a second position; means for holding said lever in engagement with the jack to keep said yarn finger in said latter position; means for releasing said lever; and a second means for moving the lever into engagement with the jack after said lever has been released by the holding means.

7. The combination in a knitting machine of a needle support; needles therein; a latch ring; a jack slidably supported by said latch ring; a finger for feeding yarn to the needles and movable by said jack into and out of operative position; a lever having one of its faces movable into engagement with the jack for moving it in a direction to throw said yarn finger out of operative position; and a spring for moving said jack in the opposite direction to throw said yarn finger into operative position, the jack, the finger and the lever being all movable in the same plane.

8. The combination in a knitting machine of a cylinder having needles; a cam ring; a member for delivering yarn to the needles; means for automatically moving said ring with said member to vary the lengths of the stitches; and means for maintaining constant the angle at which the yarn passes to the needles irrespective of the position of the cam ring.

9. The combination in a knitting machine of a needle support; a cam ring; means for automatically moving said cam ring up and down during operation of the machine; and a yarn guide connected to the cam ring so as to be moved up and down therewith.

10. The combination in a knitting machine of a needle support; a cam ring; a yarn guide; and means for simultaneously and automatically moving the cam ring and yarn guide relatively to the needle support at predetermined times during operation of the machine.

11. The combination in a knitting machine of a needle support; a cam ring; a movable structure supporting said cam ring; a member including a latch ring mounted on said structure; a yarn directing element carried by said member; and automatic means for actuating the supporting structure to move the cam ring and the yarn directing element simultaneously up or down.

12. The combination in a knitting machine of a needle support; a cam ring therefor; a structure supporting the cam ring; means for automatically actuating said structure to move the cam ring relatively to the needle support; a latch ring carried by

the supporting structure; and yarn directing means mounted on the latch ring.

13. The combination in a knitting machine of a needle support; a vertically movable structure adjacent thereto; a cam ring for the needle support carried by said structure; a latch ring also carried by the structure; a plurality of yarn guides mounted on the latch ring; and automatic means for 10 periodically imparting vertical movement to the structure carrying the cam and latch rings.

14. The combination in a knitting machine of a needle support; a latch ring; a 15 structure pivotally supporting said ring; a yarn guide; a jack for actuating said yarn guide and mounted on said latch ring; with a member for operating the jack detachably engaging the same below the pivot of the 20 latch ring.

15. The combination in a knitting machine of a needle support; a latch ring; a structure pivotally supporting said ring; a yarn guide; a jack for actuating said yarn

guide and mounted on said latch ring; with 25 a member for operating the jack engaging the same below the pivot of the latch ring.

16. The combination in a knitting machine of a needle support; a latch ring; a structure pivotally supporting said ring; 30 a yarn guide; a jack for actuating said yarn guide and mounted on said latch ring; said jack having a projection below the pivot of the latch ring; with an operating lever having a surface substantially perpendicular to 35 the line of movement of the jack, placed to detachably engage the jack projection.

17. In a knitting machine, the combination of a series of needles; means for actuating said needles; means for shifting said 40 actuating means for fashioning purposes; a plurality of yarn feeds; and means for shifting said feeds in correspondence with the shifting of the needle actuating means, whereby a constant feeding relation is at all 45 times maintained between the feeds and the needles.

ELMER U. AMES.
